(57) **CLAIM**

Dec. 5, 2005 (JP) 2005-035847

The ornamental design for an optical transmission conversion device, as shown and described.

(51) **LOC (8) Cl.** **13-02**

DESCRIPTION

(52) **U.S. Cl.** **D13/101**

FIG. 1 is a front, bottom and left side perspective view of an optical transmission conversion device, showing our new design;

(58) **Field of Classification Search** D13/101,
D13/123, 147, 199; D16/130; 385/78, 88,
385/92, 94, 125; 398/135, 182, 196–199,
398/200, 201

FIG. 2 is a front elevational view thereof;

See application file for complete search history.

FIG. 3 is a rear elevational view thereof;

(56) **References Cited**

FIG. 4 is a top plan view thereof;

U.S. PATENT DOCUMENTS

FIG. 5 is a bottom plan view thereof;
